United States Patent Office

Des. 225,970

Patented Jan. 16, 1973

225,970

SCREW

Thomas P. O'Donnell, Kings County, N.Y.
(200 Highland Blvd., Brooklyn, N.Y. 11207)

Filed Aug. 16, 1968, Ser. No. 13,167

Term of patent 14 years

Int. Cl. D8—08

U.S. Cl. D8—267

The figure shows a perspective view of a screw. The characteristic feature is the top channel at the top of the head of a screw leading to the recessed central head portion with its recessed kerf.

I claim:

The ornamental design for a screw, as shown and described.
